FILLING CLAMPING MEANS FOR LOOMS

Ivan W. Mabry, Pacolet, S. C.

Application April 26, 1948, Serial No. 23,364

2 Claims. (Cl. 139—377)

1

This invention relates to textile machinery and more especially to improvements in weft or filling thread holding devices for looms.

This invention broadly comprises means for clamping a weft or filling thread against the rear vertical plate on the shuttle box on a lay after the shuttle has passed out of the shed formed by the warp threads and into the shuttle box, at which time the lay is in its beat-up position, to thus hold the weft or filling thread taut while the weft thread is engaged by the lower free end of an improved filling fork to thus tilt the same and to thus prevent the loom from stopping.

It is an object of this invention to hold the weft or filling thread taut as heretofore described, so that the conventional grid, which is normally disposed between the reed and the shuttle box, may be eliminated.

This grid has heretofore been disposed adjacent the path of the weft or filling thread as the shuttle passes from the shed formed by the warp yarns into the shuttle box and, as the lay moves forwardly to the beat-up position, the weft or filling thread has heretofore been moved against the grid by the conventional filling fork which has heretofore been adapted to pass into slots formed by the grid and to thus tilt the conventional filling fork. When a filling thread has been used that is of very short fibre material or has very little twist to the same, the grid has heretofore collected a substantial amount of lint 30 from the weft thread and this lint would fill the spaces in the grid and although the filling thread may be broken, the filling fork would still be caused to tilt and the loom would continue to 35 run until this defect in the cloth was observed by the operator of the loom. Also, short pieces of thread disposed across the grid will give a false indication and not stop the loom using the old grid and the old filling fork.

It is another object of this invention to provide resilient means for grasping a weft or filling thread as the lay moves to a beat-up position, said resilient means being mounted on more than one lateral guiding member and one of said 40 guiding members being adjustable to adjust the resilient means so that it will engage and grasp the weft or filling thread precisely at the time intended as the lay moves to a beat-up position, or forwardly, said resilient means also being adjustable angularly so as to conform to the rear plate of a shuttle box to thus allow the resilient means to grasp the filling thread regardless of its position relative to the shuttle box plate.

Some of the objects of the invention having

2

been stated, other objects will appear as the description proceeds, when taken in connection with the accompanying drawings, in which:

Figure 1 is a perspective view of the left-hand portion of a lay, portions of a loom frame and associated parts, and showing the weft thread clamping means in the position it will occupy when the lay is in its rearmost position;

Figure 2 is a plan view of the apparatus showing the gooseneck with which it is associated and is taken along the line 2—2 in Figure 1;

Figure 3 is a vertical sectional view taken along the line 3—3 in Figure 1 and showing the lay in a beat-up position;

Figure 4 is a view similar to Figure 3 but showing the lay in its rearmost position.

Referring more specifically to the drawings, the numeral 10 indicates a lay on which the lower plate 11 of a conventional shuttle box is mounted, and this shuttle box also has integral therewith a vertically disposed plate 12, said plate being secured to a conventional sword 13, and this sword 13 also has secured thereto, by a bolt 14, one end of a reed cap 15. Mounted 25 between the reed cap 15 and the lay 10 is a vertically disposed reed 20 through the dents of which a plurality of warp yarns 21 are drawn and suitable harness frames, not shown, for a shed indicated at 22.

There is shown in Figure 1 a shuttle S which is, in this instance, disposed on the bottom plate 11 of the shuttle box and extending from the shuttle S to the warp yarns 21 and disposed between the same is the weft or filling thread 24. The plate 12 of the shuttle box and the reed 20 are disposed apart from each other to form an opening 27 in which a conventional grid is normally mounted, but, in this instance, the grid is eliminated, inasmuch as it is not deemed necessary to the efficient operation of this device.

The warp yarns 21 converge into a cloth sheet 23 which passes over a conventional breast beam 25 and extends downwardly to a conventional wind-up means, not shown.

The breast beam 25 is mounted on a conventional upwardly extending portion 26 of the loom frame and has secured on the left-hand end thereof a conventional shipper lock bracket 30 having a slot 31 therethrough at one end of which is a shoulder 32 which, when the loom is operating, serves to hold a conventional shipper handle 33 in an operating position.

Pivotedly secured on the upper surface of the breast beam 25, as at 37, is a conventional filling

motion shipper lever 40, one end of which extends outwardly beyond the end of the breast beam 25 and engages the substantially vertically disposed shipper lever 33 and the other end of which is adapted to be engaged by the front end of a conventional filling fork slide 41 which is mounted for horizontal sliding movement in a conventional filling motion stand 42. The filling motion stand 42 is secured to the upper surface of the breast beam 25 by a screw 43. The filling fork slide 41 has a spring perch 46 integral therewith and the filling motion stand 42 has a spring perch 47 integral therewith, and connected to the spring perches 46 and 47 are the two ends of a tension spring 48, to thus urge the filling fork slide 41 to the left in Figures 3 and 4 against the right-hand vertical surface of the filling motion stand 42.

The filling fork slide 41 has a gooseneck portion 50 integral therewith which extends outwardly over the lay 10 in Figure 3 and this gooseneck portion 50 has a slot 51 therethrough in which is pivotally mounted, as at 52, an improved filling fork holder 53. This filling fork holder 53 has integral therewith a U-shaped wire member 54 and, as may be observed in Figure 4, this wire 54 is adapted to intermittently engage a shouldered portion 56 of a conventional filling motion hook or snake head 57 which is pivotally mounted at one end, as at 58, on the upper end of a conventional filling cam follower dog 66, which is caused to oscillate at its upper end in a horizontal plane, by conventional means, not shown. The free end of the filling motion hook 57 slidably engages a transverse portion 66 which is integral with the gooseneck portion 50 and spans the slot 51.

The filling fork holder 41 has integral therewith, at the end opposite from the gooseneck portion 50, an outwardly projecting portion 68 which extends outwardly beyond the breast beam 25 and engages a conventional filling motion finger 70 which is fixedly mounted on a conventional starting rod which, when it is caused to partially rotate in a counterclockwise direction, as observed in Figure 3, will cause the operation of transferring a fresh supply of filling from a conventional magazine or hopper, not shown, to the shuttles.

All of the parts heretofore described are conventional parts of a loom and it is with these parts that this invention is adapted to be associated.

Although this invention is shown as being applied to the left-hand end of the loom, that is, adjacent the left-hand end of the lay, it is evident that an identical assembly may be used at the opposite end of the lay with the parts opposite hand, and it is thus not deemed necessary to describe the structure at both ends of the lay.

The bolt 52, on which the filling fork holder 53 is pivotally mounted, secures an inverted L-shaped guide member 80 to one side of the gooseneck portion 50 of the filling fork slide 41 and this inverted L-shaped guide member 80 has an arcuate slot 81 therein which is penetrated by an adjustment screw 82 which is threadably imbedded in the portion 50. The inverted L-shaped member 80 has a downwardly extending leg 85 having an elongated adjustment slot 86 therethrough, which is penetrated by a bolt 87.

The bolt 87 secures a guide block 90 to the leg 85 of the member 80 and this block 90 has mounted therein, for horizontal sliding movement, horizontally disposed and superposed

shafts 91 and 92. The shafts 91 and 92 extend to the left from the block 90, as observed in Figures 3 and 4, and have integral therewith a vertically disposed plate 95 which has adhesively or otherwise secured thereon a resilient pad 96. Surrounding the horizontally disposed shafts 91 and 92, and disposed between the block 90 and the vertical plate 95, are compression springs 97 and 98 respectively.

Threadably mounted on the shaft 92 are adjustment means in the form of nuts 100 for adjusting the distance between the vertically disposed guide block 90 and the vertical plate 95. The compression springs 97 and 98 are adapted to urge the plate 95 and the resilient pad 96, which is integral therewith, outwardly to the left as observed in Figures 3 and 4, and as the lay 10 moves from the position shown in Figure 4 to the beat-up position or as is shown in Figure 3, the plate 12 engages the left-hand vertical surface of the pad 96 and thus moves the same to the left as observed in Figures 3 and 4 against the resistance of the springs 98 and 97, and if there is a shuttle in the shuttle box there is, of course, disposed between the warp yarns 21 and the shuttle S a weft or filling thread 24.

It may be observed in Figure 1 that there is an opening 27 disposed between the conventional reed 28 and the conventional vertical plate 12, and normally this opening has disposed therein a grid against which the weft or filling thread 24 is urged by the filling fork as the lay moves to a beat-up position.

However, in this instance, it is advantageous to eliminate the grid member and instead of a conventional filling fork there is provided a substantially vertically disposed finger 110 which is curved at its upper end over the filling fork holder 53 and has an elongated slot 111 therethrough which is penetrated by a screw 112 (Figure 2), the screw being threadably imbedded in the filling fork holder 53 to thus secure the finger 110 to the filling fork holder 53.

It is thus seen that when the shuttle S has drawn a weft or filling thread across the opening 27, and as the lay moves forwardly from the position shown in Figure 4 to the position shown in Figure 3, the resilient pad 96 engages and clamps the weft yarn 24 against the vertical plate 12 and thus holds the same taut between the warp yarns and the plate 12, so that when the finger 110 engages the weft thread 24, the free end of the finger 110 will move in a counterclockwise direction from the position shown in Figure 4 to the position shown in Figure 3 to thus cause partial rotation of the filling fork holder 53 and to also raise the free end of the wire member 54.

To clarify the operation of the device, a position indicated in dotted lines and designated at 96a in Figure 1 is shown to be that location in which the resilient pad 96 engages the vertically disposed plate 12 to clamp the filling thread 24 against the plate 12.

Now, every time the lay moves to a beat-up position, the filling motion hook 57 moves from left to right in Figures 4 and 3 and in the event that there is no weft thread 24 in the path of the lower end of the finger 110, the free end of the wire member 54 will not be raised, and thus the wire member 54 will be engaged by the shouldered portion 56 of the filling motion hook 57, and thus, as the filling motion hook 57 moves from the position shown in Figure 4 to the position of Figure 3, the wire member 54 will pull the gooseneck portion 50 as well as the filling

fork slide 41 to the left in Figure 3 against the resistance of the tension spring 48.

As the filling fork slide 41 moves from left to right in Figure 3, the rear surface of the same engages the conventional filling motion shipper lever 40 to thus partially rotate the same about its pivot point 37 and its other end being in engagement with the shipper lever 33, moves the shipper lever rearwardly out of engagement with the shoulder 32 and into the slot 31 where it will automatically move from right to left, as observed in Figure 1, and will shut off the loom in a conventional manner.

In the drawings and description there has been set forth a preferred embodiment of the invention, and although specific terms are employed, they are used in a generic and descriptive sense only, and not for purposes of limitation, the scope of the invention being defined in the claims.

I claim:

1. In a loom having a lay, said lay having a shuttle box, said shuttle box having a vertical plate integral therewith, a reed disposed on the lay, said reed and said vertical plate being spaced apart from each other on the same vertical plane to thus form an opening between the same, a shuttle adapted to enter the shuttle box, said shuttle having a weft or filling thread extending from the same across the opening, said loom having a filling fork slide in which a filling fork is pivotally mounted, an inverted L-shaped guide member having the free end of its shorter leg pivotally secured to one side of the filling fork slide, the short leg of said guide member having an arcuate slot therein, an adjustment screw penetrating the arcuate slot and being threadably embedded in the filling fork slide, upper and lower horizontal shafts slidably mounted in the guide member, a substantially vertically disposed plate secured to one end of the horizontal shafts, spring means disposed around each of said shafts for urging the vertically disposed plate away from the guide member, adjustment means on one of the shafts adapted to engage the side of the guide member remote from the spring means for adjusting the position of the vertically disposed plate relative to the guide member, said vertically disposed plate adapted to be intermittently engaged by the vertical plate integral with the shuttle box for clamping the filling thread therebetween to hold the thread taut and thus prevent the same from being forced through the said opening by the filling fork and said vertically disposed plate being adapted to recede toward the guide member as the lay moves to a beat-up position, said adjustment screw associated with the arcuate slot being provided for adjusting the angularity of the vertically disposed plate.

2. In a loom comprising a lay, a shuttle box mounted on the lay, said shuttle box having a vertical plate integral therewith, a shuttle associated with the lay and having a weft or filling thread extending from the same, said loom having a breast beam on which is mounted a filling motion stand, said filling motion stand having a filling fork slide slidably mounted therein, a filling fork holder pivotally mounted in that end of the filling fork slide which is disposed adjacent the lay, a bolt penetrating the filling fork slide and on which the filling fork holder is pivotally mounted, an inverted L-shaped member having the free end of its shorter leg pivotally mounted on one end of the bolt and secured against the outer side of the filling fork slide by the same, the shorter leg of the inverted L-shaped member having an arcuate slot intermediate its ends, a screw loosely penetrating the slot and being threaded into the filling fork slide, a guide block secured to the longer leg of the inverted L-shaped member, said guide block having horizontally disposed shafts slidably mounted therein, a vertically disposed plate integral with said shafts, a resilient member secured to the vertically disposed plate, compression springs disposed between the guide block and the vertically disposed plate and surrounding said shafts to thus urge the vertically disposed plate and the resilient member associated therewith in a lateral direction away from the guide block, said resilient pad being adapted to engage the filling thread and clamp the same against the vertically disposed plate as the lay moves to a beat-up position, and said compression springs permitting the vertically disposed plate associated with the resilient pad to be moved by the vertically disposed plate on the shuttle box as the lay moves to a beat-up position to thus hold the filling thread taut while it is engaged by the filling fork, the end of one of the shafts remote from the vertically disposed plate having adjusting nuts mounted thereon to limit movement of the shafts against the pressure of the springs on the shafts.
